UNITED STATES PATENT OFFICE.

OMAR L. DAY OF PORTLAND, OREGON.

OIL-BURNER.

1,181,916.

Specification of Letters Patent. Patented Mar. 16, 1915.

Application filed October 4, 1913 Serial No. 793,386.

To all whom it may concern:

Be it known that I, OMAR L. DAY, a citizen of the United States, residing in the city of Portland, county of Multnomah, and State of Oregon, have invented certain new and useful Improvements in Oil-Burners, of which the following is a specification.

My invention relates to oil burners, and more particularly to that class of hydrocarbon burners of the character referred to in my pending application, filed January 24, 1913, under Serial No. 743,999.

The principal object of this invention is to provide certain improvements in the construction and arrangement of oil burners of the character referred to and which are adapted for burning kerosene, distillate and the like, by means of which improvements I am able to secure greater efficiency, safety, economy and cleanliness.

In order to secure a perfect combustion from burners of this character, with little or no odor or soot, it is necessary that the oil be first thoroughly gasified, then thoroughly mixed with the proper amount of air, and this mixture again heated before being delivered for combustion. I am able to get better results from my burners because I discharge the gasified oil and air from the mixing chamber into a superheating chamber where it is reheated before being delivered to the burner for combustion.

In this invention I have provided certain improvements in the mechanical construction of the burner, whereby I am able to reduce the initial cost of the burner and whereby I am able to get a more uniform distribution of the combustion outlets without losing any of the advantages of the principle of my burner.

I have shown in the accompanying sheet of drawing, my preferred form of burner, which I will now describe.

Figure 1 is a top plan view of the burner; Fig. 2 is a longitudinal sectional view on line 2--2, Fig. 1; Fig. 3 is an end elevation of the burner. Fig. 4 is a cross sectional view on line 4--4 of Fig. 1; and Fig. 5 is a longitudinal sectional view through Fig. 4 taken on the line 5--5 of said figure.

In the drawings, 1 designates a supply pipe for the fuel oil, 2 a valve for controlling the admission of the oil to the vaporizer 3, formed of the pipes 3--3, coupled together as shown. Said vaporizer connects

at its discharge end with a T 4, which is provided at its opposite sides with nipples 5 and 6. The nipple 5 is provided with a sleeve 7, within which is placed a plug 8, and a disk 9, having a threaded opening therethrough to receive a needle valve stem, as 10, adapted to control a discharge opening 11, in the end of a cap 12, mounted upon the end of the nipple 6. Any suitable packing may be placed in said sleeve between the disk 9 and the plug 8, as indicated. A four-way member, or cross, as 13, constituting a mixing chamber is attached at one side of the nipple 6, by means of a bushing 14, with the needle valve discharge within said cross 13, as indicated. The side of said cross 13, opposite the needle valve discharge 11, is provided with a section of pipe, as 15, which constitutes a superheating chamber, hereinafter again referred to, 16 designated by me, as indicated. The burner body and comprises a box-like casing into the interior of which the superheating chamber 15 discharges through an elbow 17 and a nipple 18. Said burner body is provided in its upper side with a series of upwardly projecting discharge teats, as 19, and also with a flange 20 around the upper outer edge, whereby to constitute the upper side of said burner body a generating pan into which a quantity of oil can be discharged for generating purposes. The cross 13 which constitutes the mixing chamber, is provided with a downwardly extending nipple 21, which passes through an opening through the burner body, but not communicating with the interior thereof, in the manner indicated, said nipple extending down into the ash pit, for example, if the burner is placed in the fire box of a kitchen range. The upper outlet of said cross 13 is provided with a detachable plug, as 22, which may afford access to the interior of the mixing chamber and to the end of the needle valve. The supply pipe 1 is provided with a T, as 23, to which is attached a needle valve, as 24, with a spout 25, whereby to supply a quantity of oil to the top of the burner body for generating purposes, the oil filling in around the teats 19, but not rising high enough to pass through said teats 19 and into the body 16 of the burner.

In order to facilitate the heating and gasifying of the oil as soon as it enters the gasifier 3, I insert into the entrance end of said gasifier pipe 3, a small roll of wire fabric, 26

as 26, Figs. 4 and 5, which becomes heated so that as the oil passes therethrough it is heated somewhat before it gets far into the hot pipe 3 in which it is thoroughly gasified.

5 It will be noted that the gasifying pipes 3-3, the mixing chamber 13 and the superheating chamber 15 are all directly over the burner body, and that the combustion is uniformly distributed therebeneath, whereby to 10 get the best results. It will also be noted that the air to be mixed with the gasified oil and which enters the mixing chamber 13 through the nipple 21, is drawn in from the space in the stove below the fire box, assuming that the burner is placed in the fire box 15 of a kitchen range, thereby using air which is slight-warmed and dried.

While I have shown and described the preferred form of the invention, I am aware 20 that changes can be made therein without departing from the spirit of the invention, and I do not limit the invention to this particular form, except as I may be limited by the hereto appended claims.

25 I claim:

1. In a burner of the character referred to, in combination, a pipe section constituting a gasifying chamber into which oil is discharged, a hollow burner body beneath 30 said pipe section and having a top adapted to receive oil thereupon for generating purposes, with combustion teats projecting upwardly therefrom through any oil thereupon and communicating with the interior 35 of said burner body, and means connecting said pipe section and the gasifying chamber therein with the interior of said hollow burner body, whereby the gas from said gasifying chamber is discharged into said burner body and through said teats for combustion.

2. In a burner of the character referred to, in combination, a pipe section constituting a gasifying chamber with means for 40 supplying oil thereto, a second pipe section constituting a superheating chamber with means for admitting air thereto and into which said gasifying chamber discharges, a hollow burner body beneath said pipe sections and having a top adapted to receive oil thereupon for generating purposes, and provided with a series of combustion teats 50 projecting upwardly therefrom through any oil thereupon and forming combustion outlets from said burner body, and means connecting said superheating chamber with said burner body, whereby the gas from said chamber is discharged into said burner body and through said combustion teats, for the 55 purpose referred to.

60 3. An oil burner of the character referred to, comprising in combination a pipe section constituting a gasifying chamber, a cross open at one side to admit air and constituting a mixing chamber, a needle valve

mechanism connecting said gasifying chamber with said mixing chamber, a pipe section connected with said cross and constituting a superheating chamber, and into which the mixture from said mixing chamber is 70 discharged, a hollow burner body underlying said gasifying, mixing and superheating chambers and into which said superheating chamber discharges, said burner body having a flange around its upper edge and a 75 series of teats opening therefrom and constituting combustion outlets, and means for supplying a quantity of oil for generating purposes on to the top of said burner body, and around said teats, substantially as referred to.

4. In a vapor or gas burner, a burner body of hollow box-like construction provided with an open pan-like top having a series of upwardly projecting outlet members formed integrally therewith, said top being constructed to receive therein oil for generating purposes, means for supplying vapor or gas to the interior of said body, and means for supplying oil or the like to 90 the pan-like top thereof.

5. In an oil burner of the character referred to, a burner body of hollow construction having a series of combustion teats projecting upwardly therefrom and communicating therewith, and a flange around its upper outer edge whereby to constitute the top of said burner body a generating pan, said burner body having an opening formed therethrough but not communicating with 100 the interior thereof, substantially as and for the purpose described.

6. A burner of the character referred to comprising in combination, a member constituting a gasifying chamber with means 105 for admitting oil thereto, a hollow burner body having a pan-like top to receive oil for generating purposes, portions of said top projecting upwardly therefrom and having outlet combustion openings from the interior of said burner body above the oil upon the top thereof, whereby to prevent oil from getting into said openings, and means connecting said gasifying chamber with the interior of said burner body, with an air inlet for supplying air to said gas mixture, substantially as described.

7. In a burner of the character referred to, in combination, a gasifier, into which the fuel is discharged, a mixing chamber, means 120 providing a restricted communicating opening from said gasifier to said mixing chamber, means for admitting air to said mixing chamber, and a burner body underlying said gasifier and mixing chamber and into which said mixing chamber discharges the mixture, said burner body having means upon its upper side to receive a quantity of oil for generating purposes, and upwardly projecting members with gas outlets there- 125 130

through from the interior of said burner body for combustion purposes, substantially as described.

8. An oil burner comprising in combination, a loop of pipe constituting a gasifying chamber and into one end of which the fuel oil is discharged, a cross constituting a mixing chamber with which the opposite end of said pipe connects, a needle valve mechanism interposed between the chamber and pipe to regulate the discharge from said gasifying chamber to said mixing chamber, a pipe section constituting a super-heating chamber communicating with said cross and lying between the looped portions of said loop of pipe, a burner body of hollow construction underlying said gasifier and said super-heating chamber and having a series of combustion outlets from the upper side thereof, and a nipple member extending through said burner body and communicating with the lower side of said cross, whereby to admit air to said mixing chamber, substantially as described.
9. An oil burner comprising in combination, a loop of pipe constituting a gasifier,

a valve for controlling the admission of oil thereto, a cross, a needle valve mechanism connecting the opposite end of said looped pipe with said cross, a pipe section from the opposite side of said cross and constituting a super-heating chamber, a burner body of hollow construction with which said super-heating chamber communicates, said burner body having a top formed as a pan to receive oil for generating purposes and a series of upwardly projecting combustion teats opening from said burner body, a nipple extending through said burner body and connected with the underside of said cross for supplying air to said mixing chamber, and means for supplying a quantity of oil to the top of said burner body for generating purposes, substantially as shown and described.

Signed at Portland, Oregon, this 29th day of September, 1913.

OMAR L. DAY.
